Primary Examiner — Elizabeth J Oswecki(74) Attorney, Agent, or Firm — Harness, Dickey & Pierce, P.L.C.CLAIM

The ornamental design for hole-patterned motif, as shown and described.

DESCRIPTION

FIG. 1 is a right perspective view of a hole-patterned motif showing my new design;

FIG. 2 is a left side view thereof;

FIG. 3 is a right side view thereof;

FIG. 4 is a top plan view thereof;

FIG. 5 is a front perspective view thereof; and,

FIG. 6 is a back perspective view thereof.

The broken lines shown in all of the figures are for environmental purposes only and form no part of the claimed design. All surfaces not shown form no part of the claimed design.
